FIGURE 1 is a front perspective view of a chair, showing my design; FIGURE 2 is a rear perspective view of the chair with the legs removed for convenience of illustration; FIGURE 3 is a side elevational view of the chair; and FIGURE 4 is a plan view of the chair.

The dominant features of the design reside in the portions shown in full lines on the drawing.

I claim:

The ornamental design for a chair, as shown and described.
